UNITED STATES PATENT OFFICE.

JOHN SCOTT, OF GRAND RAPIDS, MICHIGAN, ASSIGNOR TO BISSELL CARPET SWEEPER COMPANY, OF GRAND RAPIDS, MICHIGAN, A CORPORATION OF MICHIGAN.

DESIGN FOR A LAMP-SHADE.

43,726.

Specification for Design.

Patented Mar. 18, 1913.

Application filed December 4, 1912. Serial No. 734,994. Term of patent 3½ years.

To all whom it may concern:

Be it known that I, JOHN SCOTT, a citizen of the United States, residing at Grand Rapids, in the county of Kent and State of Michigan, have invented a new, original, and ornamental Design for Lamp-Shades, of which the following is a specification, reference being had to the accompanying drawing, forming part thereof.

The figure is a perspective view of a lamp shade showing my design.

I claim:

The ornamental design for a lamp shade, as shown.

JOHN SCOTT.

Witnesses:

PALMER A. JONES,
RAY W. LONGFIELD.
